BORE FINISHING TOOL

Earl A. Thompson, Ferndale, Mich.

Application December 7, 1955, Serial No. 551,572

4 Claims. (Cl. 29—90)

This invention relates to an apparatus for finishing cylindrical bores in work pieces and has to do more particularly with a tool adapted to provide the bore of a work piece with a hardened, extremely smooth and very accurate cylindrical surface.

In the drawings:

Fig. 1 is a side elevational view partly in section of the apparatus according to the present invention.

Fig. 2 is a sectional view along the lines 2—2 in Fig. 3 and showing the expanding arbor at the front end of the apparatus illustrated in Fig. 1 and further showing the work piece arranged thereon.

Fig. 3 is a sectional view along the lines 3—3 in Fig. 2.

Fig. 4 is a detail sectional view of the check valve employed in the arrangement shown in Fig. 1.

Referring particularly to Fig. 2, the tool proper is in the nature of an expanding arbor generally designated 10 which includes a hollow spindle 12. Spindle 12 is fashioned as a tubular member having a side wall 14 of uniform thickness and an end wall 16. The outer surface of side wall 14 is accurately ground to true cylindrical shape. Around the outer surface of side wall 14, there are arranged finishing rollers 18 and guide pins 20.

As is seen more clearly in Fig. 3, it will be observed that a guide pin 20 is arranged between successive pairs of finishing rollers 18. These rollers and guide pins are supported around the outer surface of the side wall 14 by a front retainer 22 and a rear retainer 24. The front end wall 16 of member 12 is fashioned with a reduced threaded portion 26, and the front retainer 22 is in the form of a cap having a threaded end 28 engaged with the threaded end 26 of member 12. Retainer 22 has a cylindrical wall portion 28 telescoped over the outer surface of wall 14 and at the free end thereof is provided with an annular flange 30 fashioned with a conically-shaped race 32. Rear retainer 24 has a slip fit on spindle 12 and is provided with a conically-shaped race 34 at the end thereof. Retainers 22 and 24 are spaced axially apart on spindle 12 so that the races 32 and 34 engage the conically-shaped opposite ends 36 of the finishing rollers 18 and maintain these rollers in contact with the outer surface of the side wall 14 of spindle 12. At circumferentially spaced points corresponding to the spacing of rollers 18, the rear retainer 24 is fashioned with sockets 38 in which the rear ends of the guide pins 20 are press fitted. Thus, as is seen in Fig. 3, guide pins 20 maintain the finishing rollers 18 in true axial alignment with the axis of spindle 12. The retainers 22 and 24 with pins 20 thus form a cage for constraining the rollers 18 to positions adjacent the arbor and parallel thereto. The bore of retainer 24 adjacent the race 34 is preferably undercut as shown at 40. The bore of the cylindrical wall portion 28 of retainer 22 may be similarly undercut, if desired; but since retainer 22 is of relatively light section as compared with retainer 24, undercutting of the bore of retainer 22 has not been found to be necessary. It will be observed that the annular flange 30 of retainer 22 has an outer diam-

2

eter less than the circle formed by the radially outermost surfaces of rollers 18, thus enabling a work piece such as shown at 42 to be slipped over the end of the arbor 10 with its bore 44 contacting rollers 18.

With this arrangement, it will be observed that if spindle 12 is rotated and bore 46 thereof is subjected to a relatively high internal pressure, the side wall 14, or at least the portion of side wall 14 between retainers 22 and 24, will be generally uniformly expanded to rotate rollers 18 by bringing them into substantial pressure contact with the bore 44 of work piece 42. At the same time, if the work piece 42, which in the arrangement shown comprises the body of the hydraulic valve lifter, is prevented from turning, a very smooth, hard and truly cylindrical surface will be provided on the bore 44 thereof. Rollers 18 are, of course, driven with spindle 12 by reason of the drive provided by guide pins 20. It will be appreciated, of course, that best results are obtained by first forming the bore 44 with a very smooth and accurately dimensioned surface. If, after the bore is formed in this manner, such as by boring, it is telescoped over the rollers 18 as illustrated in Fig. 2 and the spindle 12 rotated and subjected to pressure sufficient to expand the side wall 14 a very small amount, for example, a few millionths of an inch, a mirrorlike hardened surface will be formed on the bore 44 of the work piece 42. The bore 44 will thereafter be admirably suited for use as a cylinder in which a piston of the hydraulic valve lifter may operate.

30 The means employed for rotating spindle 12 and for subjecting the interior thereof to an expanding pressure may take several forms. In the embodiment illustrated in Fig. 1, these means are in the form of a base 48 on which is supported a rather large cylinder 50. At one end, cylinder 50 is provided with a suitable fitting 52 for connecting the cylinder with a source of air under pressure; and from the opposite end of the cylinder, a plunger 54 projects. Plunger 54 is connected with a piston 56 that operates within cylinder 50. At its free end, plunger 54 is fashioned with a hub 56 provided with a bore 58. Within bore 58, there is press fitted the outer race of a bearing 60. The inner race of bearing 60 has press fitted therein a piston member 62. Piston 62 is arranged to slide axially within the bore 64 of a cylinder 66. Cylinder 66 is supported for rotation in a bearing block 68 by ball bearings 70 and 72. Cylinder 66 has keyed thereon a pulley 74 having a belt drive 76 with a motor, not illustrated. A clamping nut 78 is employed for clamping pulley 74 on cylinder 66. Disc 78 on piston 62 is slidably engaged with pins 80 on pulley 74 so that the piston 62 rotates in bearing 60 with cylinder 66 and is adapted to move axially relative thereto. Hub 56 on plunger 54 is prevented from rotating by means of a pin 82 on the hub which engages in an axially extending groove 84 in base 48. Piston 62 is normally biased in a direction out of cylinder 66 by a compression spring 86.

An oil reservoir 88 is mounted on hub 56, and the hub 56 has a passageway 90 therein which connects with reservoir 88 and with an oil chamber 92 in the hub. Piston 62 has an axial bore 94 extending therein and communicating at its rear end with oil chamber 92. Chamber 92 is sealed around piston 62 by an oil seal 96. At its front end, the axial bore 94 in piston 62 communicates with the bore 64 of cylinder 66 and is controlled by a check valve in the form of a ball 98 biased to seat against the end of the piston by means of a spring 100. Expanding arbor 10 is mounted at the front end of cylinder 66 by a threaded fitting 102, and an axial passageway 104 in cylinder 66 connects bore 64 with the bore 46 of the spindle 12.

When it is desired to finish the bore of a work piece such as shown at 42, the work piece is slipped over the end of the expanding arbor 10 as shown in Fig. 2. The

motor drive with which the belt 76 is connected is then operated so as to rotate the arbor. Thereafter, air under pressure is admitted to cylinder 50 through fitting 52 to advance the piston 56 axially therein. At this time, it will be appreciated that the oil level in reservoir 88 will maintain the bore 46, the axial passageway 104, bore 64, passageway 94 and oil chamber 92 filled with oil. Since plunger 54 moves forwardly, ball check 98 seats against the outer end of piston 62; and pressure is thus applied to the oil in the bore 46 of spindle 12. The air pressure applied to cylinder 50 is controlled so as to obtain the desired relatively high pressure within spindle 12 to thus expand the side wall 14 of the spindle and cause the rollers 18 to roll with high pressure contact against the bore 44 of the work piece.

I claim:

1. A tool for finishing cylindrical bores comprising an elongate tubular member closed at one end and having means adjacent its other end for connection with a source of fluid under pressure, said member having an outer surface portion of true cylindrical shape which is adapted to be radially expanded when the member is subjected to high internal pressure, a plurality of rollers arranged circumferentially around said cylindrical surface portion and extending axially thereof, said rollers having an axial extent substantially less than said tubular member and terminating at their opposite ends substantially inwardly of the opposite ends of the tubular member and means for supporting said rollers for rolling contact with said cylindrical surface portion.

2. A tool for finishing cylindrical bores comprising a tubular member closed at one end and having means adjacent its opposite end for subjecting the interior of said tubular member to hydraulic pressure, said tubular member having an outer surface portion of true cylindrical shape, a plurality of cylindrical metal finishing rollers arranged circumferentially around said cylindrical surface portion, said rollers having their opposite ends terminating substantially inwardly of the opposite ends of said tubular member and said cylindrical surface extending axially beyond the opposite ends of said rollers, retainer means on said tubular member for supporting said rollers in rolling contact with said cylindrical surface portion and means for rotating said tubular member about the axis of said cylindrical surface portion.

3. A roller burnishing tool for finishing an internal bore comprising a hollow mandrel having a thin wall of uniform thickness and forming a true circular cylinder, means including a body of liquid for exerting within the mandrel an expanding pressure acting uniformly in all directions, a plurality of burnishing rollers of circular cylindrical form and of a length which is several times their diameter positioned in rolling contact with the outside of the mandrel, cage means acting to constrain the burnishing rollers parallel to the mandrel and adjacent thereto and a stem forming a rotary driving connection and having a fluid conduit connecting with the interior of the mandrel.

4. A roller burnishing tool for finishing the interior of a circular bore comprising a set of burnishing rollers which are slender true circular cylinders, a mandrel comprising a thin wall, longer than the rollers and having an uninterrupted truly circular outer surface of uniform diameter throughout its length, a cage for retaining the rollers adjacent the mandrel and in position parallel to the mandrel, means including a body of liquid for exerting radially outward expanding pressure directly and uniformly along the full length and around the full circumference of the mandrel, a stem for rotating the mandrel and having a conduit connection to the interior of the mandrel.
